UNITED STATES PATENT OFFICE.

JOSEPH A. HEALY, OF LYNN, MASSACHUSETTS.

DESIGN FOR A PEN-WIPER HOLDER.

SPECIFICATION forming part of Design No. 27,853, dated November 16, 1897.

Application filed September 27, 1897. Serial No. 653,263. Term of patent 7 years.

To all whom it may concern:

Be it known that I, JOSEPH A. HEALY, of Lynn, in the county of Essex and State of Massachusetts, have invented and produced a certain new and original Design for Pen-Wiper Holders, of which the following is a specification, reference being had to the accompanying drawings, forming a part hereof.

Figure 1 is a side view of a pen-wiper holder, showing my design. Fig. 2 is an edge view of the same. Fig. 3 is a perspective view. Fig. 4 is a section on line 4 4 of Fig. 2.

The leading feature of my design consists in two plates connected by a curved U-shaped neck, the plates having their longer edges bent inwardly to form flanges.

a a represent the plates. *b* represents the neck connecting the plates, and *c c* represent the flanges extending along the longer edges of the plates.

20

I claim—
The design for a pen-wiper holder, substantially as shown and described.

In testimony whereof I have signed my name to this specification, in the presence of 25 two subscribing witnesses, this 23d day of September, A. D. 1897.

JOSEPH A. HEALY.

Witnesses:

A. D. HARRISON,
P. W. PEZZETTI.
